APPARATUS FOR TURNING CIGARETTES RIGHT SIDE UP AS THEY ARE FED TO THE
PACKING MACHINE

Application filed July 1, 1929, Serial No. 375,264, and in Germany May 23, 1928.

In devices for the mechanical packing of cigarettes and similar articles it is usual for the feeding device, which carries the cigarettes to the packing machine, to divide them 5 into one or more rows or sets, so that they can be observed by the operator attending to the machine, and in the event of their not being in the right position, turned so that they lie right side up.

10 It has previously been suggested that the turning of the wrongly placed cigarettes into the face upward position should be effected, instead of directly by hand, by some mechanical device actuated by the pressing 15 of a key or by operating a hand lever, or in some other suitable manner and capable of giving the cigarette, etc., as it is carried forward, a turn of 180°. In actual use these devices have been found to suffer from the 20 drawback that when the row of cigarettes is moving quickly the operator is not always able to scrutinize them quickly enough, and also that constant observation of the rapidly 25 moving cigarettes soon produces fatigue.

The result is that the turning device is often brought into action too soon or too late, so that instead of the proper cigarette it is one in front of it or behind it that is turned.

30 According to the present invention this drawback is overcome by having a certain number of the cigarettes as they are moved forward by the feed device held, by means of an optical device, in a position of apparent rest in relation to the observation post 35 within which the control of the turning mechanism is contained, so that the operator, or alternatively the automatic turning device employed, which may embody a photo electric cell, a selenium cell, or some other arrangement subject to a certain amount of inertia, has sufficient time to detect the cigarettes in relation to the devices necessary for turning them and to operate the proper 40 release.

The appended drawings show by way of examples some forms of the invention, and:—

45 Fig. 1 is a diagrammatic representation 50 of a device in which the apparent position of

rest of the cigarettes to be observed is obtained by optical means.

Fig. 2 is a plan view of the image holder by itself.

Fig. 3 is a diagrammatic view of the 55 whole of the arrangement whereby the turning device is actuated.

Fig. 4 is a section through Fig. 3 on the line A—B.

Fig. 5 is a side view of one part taken 60 from Fig. 3.

The cigarettes to be packed are conveyed in the usual manner by a device, which, in the examples shown, consists of a chain moving at a uniform speed. The links 10 of 65 this chain are held together by pins 11.

The links 10 are provided with grooves 12, in which the cigarettes 13 lie in an oblique position. The grooves 12 have raised edges indicated by 14, Fig. 3, against which the 70 cigarettes rest. At suitable places along the line of travel one or more stops 15 are placed these being vertically movable up and down in guides 16, and so placed that when in the upward position they engage the cigarette 75 as it moves along, straightening it and giving it a turn of 180°.

An optical system consisting of two double convex lenses 17 and 18, and a mirror 19 is placed in a position above the line of 80 travel and projects upon a translucent screen 20, an image 13¹ of a certain number of the cigarettes 13, in this example eight. The lens 18 and mirror 19 are placed at a definite angle to each other, and mounted in a tube shaped container 21, Fig. 1, which by means of two guide-rods 22 and 23 is carried in a direction parallel to the line of travel of the cigarettes 13, and by means of suitable driving mechanism, which may consist of a cam disc or the like, is caused to move at a speed governed by the speed of travel of the cigarettes themselves, and to return quickly to its original position. The lens 17 is placed within a tube 24 fitted into the 85 lower end of the container 21, the lower extremity of tube 24 being above the line of travel of the cigarettes.

The opaque screen 20 is connected to the 90 container 21 by means of an extensible belt 100

lows, so that it shall not move with the container 21. The image of the eight cigarettes 13 to be observed is projected by the lenses 17, 18 and by the mirror 19 upon the opaque screen 20 where, owing to the movement of the container 21, the image appears stationary until all the eight cigarettes 13 have been carried past. This gives the observer operating the turning device sufficient time 10 to note whether the cigarettes appearing on the opaque screen 20 are in the right position, and if one or more of the eight cigarettes are wrongly placed he is easily able to actuate the turning device. The time at 15 the operator's disposal for noting whether the cigarettes are in the correct position is therefore eight times as long as it is when he has to observe them directly on the chain, as the opaque screen provided him, instead 20 of the rapidly changing image of a single cigarette, with a picture of eight cigarettes shown simultaneously and apparently motionless.

The turning device is released by means 25 of a set of push keys 33 placed by the side of the cigarettes or of their images.

These keys, eight in all, are in fixed positions and the image of the eight cigarettes momentarily under consideration is, as explained above, projected on to the screen 20 by means of the optical device in such manner that during the time required the eight cigarettes remain constantly opposite to the eight keys.

The keys 33 are connected to electric circuits 35¹, 35², etc., which are closed by pressure on the keys. The wires 35¹, 35², and so on are jointly connected to one pole of a battery 36^a, the other pole of the battery 30 being connected to a return wire. Each of the wires 35¹, 35², etc. leads to a roller or rubbing contact 37 made of conductor material which is placed at the periphery of a revolving disc 36 driven by any form of 40 power. There are eight of these contacts working on the same axis and each one of them contacts with a slip ring 38 on the periphery of the disc 36.

Within the disc 36 are a number of electromagnets 39, Fig. 4, in the present instance 24 altogether, that is to say three times as many as the number of push keys. The number of electromagnets being three times as large as the number of wires 35¹, 35² and so on, the slip rings 38 are subdivided into three parts disposed around the periphery of the disc 36. Each one of the electromagnets 39 is connected by a conductor 40 to one of the eight slip rings 38. Two other discs, 41 and 42, Fig. 4, are permanently connected to disc 36. Disc 41, which is of smaller diameter than 36 and 42, the latter preferably being equal, has on its periphery a coating of conductor material 60 43, connected by wires 44 with the adjacent

ends of the magnet windings of all the electromagnets 39. In contact with the coating 43 is a roller or rubbing contact 45, connected to the return wire 35 of the electric circuit. 70

In the disc 42 are longitudinally slidable magnet armatures 46, placed opposite to the electromagnets on disc 36, so that these armatures 46 are likewise 24 in number. The armatures 46 are generally arranged in the 75 positions shown in Fig. 4, so that as they pass by the free end of an elbow lever 48 connected to the stop 15 of the turning device they hold the lever in such a position that the stop 15 of the turning device does not project into the path of travel of the cigarettes. When, however, the circuit of one of the electromagnets 39 is closed by pressing down the appropriate key 33, the respective armature 46 is attracted, so that on the subsequent passage of the armature 46 the lever 48 is released and is moved by the action of a spring 50 into such a position that the stop 15 is in the raised positions causing it to come up against the cigarettes 13 as it moves forward and to give it a turn of 180°. The speed of rotation of discs 36 and 42 is so calculated that the passage of the attracted armature 46, and consequently the release of lever 48 shall occur at the moment in which the particular cigarettes 13, the incorrect position of which gave cause for pressing down the key 33 and thereby closing the circuit, has arrived in front of the stop 15 of the turning device, so that in every case it is the right cigarette 90 that is turned.

For the purpose of effecting the return movement of the attracted armature 40, there is placed by the side of disc 42 an inclined surface 51 (Fig. 5) which has effect, as disc 42 continues to rotate, of pushing the armatures 42 back into the position shown in Fig. 4. 105

The transmission by optical means of the image of the cigarettes to be observed on to a screen presents this special advantage that the image can be produced at any place found most convenient. It follows that where there are several feed tracks in just a position to each other the operator who has to actuate the turning device need not, as hitherto, be posted between the feed tracks, the latter can be placed close together and the operator's position can be wherever desired, which results in an appreciable saving of space. 110

With optical transmission it is also not absolutely necessary that the optical system itself should move, as it does in the example shown in Figs. 1 and 2. This can instead be so arranged that the screen on to which the image of the cigarettes is projected moves at a speed governed by the speed of travel of the cigarettes, and that 125 130

5 after traversing a distance equal to the separation between the first and last of the set of cigarettes, shown on the screen, it is brought rapidly back to its original position, the cycle of operations being then repeated. This can be suitably arranged by providing the bellows sufficiently rigid so that the screen will move together with the container 21.

10 Furthermore, the invention is of course equally well utilizable in those cases where the actuation of the turning devices is effected not by mechanical means through the agency of an operator winding the machine, but by automatic means utilizing the 15 sensitiveness of photo-electric cells, selenium cells, or other devices.

I claim:—

20 1. A device for enabling the turning of cigarettes on a conveyor as they are fed to a packing machine comprising optical means adapted to throw a stationary image of the moving cigarettes for the purpose of enabling an appliance to be operated to turn any desired cigarette shown in the image; and means for observing the image.

25 2. A device for enabling the turning of cigarettes on a conveyor as they are fed to a packing machine comprising a screen; and 30 optical means adapted to throw a stationary image of the moving cigarettes on the screen for the purpose of enabling an appliance to be operated to turn any desired cigarette shown in the image.

35 3. A device for enabling the turning of cigarettes on a conveyor as they are fed to a packing machine comprising optical means including a mirror and a screen on which a stationary image of the moving cigarettes 40 is adapted to be thrown, said mirror being movable in a manner governed by the speed of motion of the cigarettes so that the image of the cigarettes as thrown on the screen remains in a position of apparent rest for a 45 period corresponding to the distance between the previous and the next set, for the purpose of enabling an appliance to be operated to turn any desired cigarette shown in the image.

50 4. A device for enabling the turning of cigarettes on a conveyor as they are fed to a packing machine comprising optical means including a system of lenses, a mirror and a screen on which a stationary image of the 55 moving cigarettes is adapted to be thrown, said mirror and lenses being movable in a manner governed by the speed of motion of the cigarettes so that the image of the cigarettes as thrown on the screen remains in a 60 position of apparent rest for a period corresponding to the distance between the previous and the next set for the purpose of enabling an appliance to be operated to turn any desired cigarette shown in the image.

55 5. A device for enabling the turning of

cigarettes on a conveyor as they are fed to a packing machine comprising an optical system; and a screen on which a relatively stationary image of the moving cigarettes is adapted to be thrown by the optical system, 70 said screen moving with a speed corresponding to that of the cigarettes and being adapted to be brought back to its original position for the purpose of enabling an appliance to be operated to turn any desired 75 cigarette shown in the image.

6. A device for enabling the turning of cigarettes on a conveyor as they are fed to a packing machine comprising an optical system; and a screen on which a relatively 80 stationary image of the moving cigarettes is adapted to be thrown by the optical system, said screen moving with a speed corresponding to that of the cigarettes and being adapted to be brought back to its original 85 position for the purpose of enabling an appliance to be operated to turn any desired cigarette shown in the image by means of a plurality of push keys arranged adjacent the screen and equal in number to the cigarettes shown in the image on the screen.

In testimony whereof I affix my signature.

MARTIN BERGER.
